UNITED STATES PATENT OFFICE.

THEODORE F. CONKLIN, OF FOND DU LAC, WISCONSIN, ASSIGNOR, BY MESNE ASSIGNMENTS, TO THE CONKLIN TRUNK BOLT COMPANY, (LIMITED,) OF SAME PLACE.

TRUNK-CATCH.

SPECIFICATION forming part of Letters Patent No. 311,721, dated February 3, 1885.

Application filed July 31, 1884. (No model.)

To all whom it may concern:

Be it known that I, THEODORE F. CONKLIN, of Fond du Lac, in the county of Fond du Lac, and in the State of Wisconsin, have invented 5 certain new and useful Improvements in Trunk-Catches; and I do hereby declare that the following is a full, clear, and exact description thereof.

My invention relates to trunk-catches or box- 10 fasteners, and is in part an improvement on the device patented by me on the 11th of September, A. D. 1883, and numbered 284,615; and it consists in certain peculiarities of construction, as will be more fully set forth here- 15 inafter.

In the drawings, Figure 1 is a vertical section, in side elevation, of my improved device as locked. Fig. 2 is a rear elevation of the same. Fig. 3 is a like view of the working parts when the latch is in position as unlocked. Fig. 4 is an under side perspective view of the latch. Fig. 5 is a front elevation of my trunk-catches separated.

A is the box-plate, which is provided with 25 a pin, a, projecting from the inside of its front face.

A' is a catch-plate, which is pivoted on the pin a, and is maintained in position with its retaining-lug a', that projects out from its free 30 end, resting against the inside face of the box-plate A by means of a spring, a², coiled around the said pin a, secured thereon in any suitable manner. The said catch-plate A' is provided in about its center with a pin, a³, projecting from its front face, and through an oblong perforation, a⁴, cut across the front 35 face of the box-plate A. The free end of the catch-plate A' is rounded, and the upper end of its retaining-lug a' is cut on a bevel, so as 40 to be readily moved out of the way of the catching-hasp described below.

B is the upper catch-plate. This is provided on its lower edge with the hasp b, projecting vertically from it on a plane slightly 45 inward of the front face of the box-plate A, wherein it is received when the trunk or box is closed. The said hasp is perforated in its center, as shown at b', to receive the retaining-lug a' of the catch-plate A'. On one side 50 of the hasp b, I provide a finger, b², which projects slightly downward, with its point bent inward, as shown. This finger is designed to

guide the hasp safely down into the box-plate and to move the catch-plate A' in position for locking. The edge of this latter corresponding to the said finger b² is suitably cut away 55 to enable the said finger to slip out of the plate readily.

The operation of my improved catches is easily understood. They are self-locking, as 60 the moment the finger b² has entered the box-plate the catch-plate is brought in position to fall in the perforated hasp b. The unlocking is effected by simply moving the pin a to 65 ward the finger b², or to the opposite edge of the oblong slot or perforation through which it projects. This motion will cause the retaining-lug a' to be raised out of the hasp, when, as the trunk or box lid is raised, the finger of this latter will move the catch-plate, 70 with its lug a', in position to lock again.

Having thus described my invention, what I claim as new, and desire to secure by Letters Patent, is—

1. In a trunk-catch, the combination, with 75 the box-plate transversely perforated and provided with an inwardly-projecting pin, of a catch mounted on said pin and having a retaining-lug at its free end, and a pin projecting through the hole in the box-plate, said 80 catch having also one side cut away or rounded out, and another plate having a stationary hasp rigid therewith, provided with a hole for engagement with the lug on the catch, and an inwardly-projecting finger at one side for engagement with the cut-away portion of the catch, substantially as and for the purpose set forth.

2. In a trunk-catch, the combination of the box-plate A, having pin a and transverse slot 90 a⁴, catch A', cut away or rounded out at one side, and having lug a' and pin a³, spring a², and plate B, having stationary hasp b, provided with perforation b' and finger b², substantially as set forth.

In testimony that I claim the foregoing I have hereunto set my hand, at Milwaukee, in the county of Milwaukee and State of Wisconsin, in the presence of two witnesses.

THEODORE F. CONKLIN.
